[57] CLAIM

The ornamental design for a receptacle for a roll of paper, as shown and described.

DESCRIPTION

FIG. 1 is a rear and left side perspective view of a first embodiment of my design;

FIG. 2 is a top plan view of the first embodiment of my design;

FIG. 3 is a rear elevational view of the first embodiment of my design;

FIG. 4 is a side elevational view of the first embodiment of my design, it being understood that the side opposite to that shown is a substantial mirror image thereof;

FIG. 5 is a front elevational view of the first embodiment of my design;

FIG. 6 is a bottom plan view of the first embodiment of my design;

FIG. 7 is a rear and left side perspective view of a second embodiment of my design;

FIG. 8 is a side elevational view of the second embodiment of my design, it being understood that the side opposite to that shown is a substantial mirror image thereof;

FIG. 9 is a front elevational view of the second embodiment of my design; and,

FIG. 10 is a top plan view of the lid of the second embodiment of my design.

Fig. 1.
